UNITED STATES PATENT OFFICE.

JOHN W. MOORE AND JOSEPH ATWOOD WHITE, OF PHILADELPHIA,
PENNSYLVANIA.

PAPER-MAKING MACHINE.

SPECIFICATION forming part of Letters Patent No. 694,772, dated March 4, 1902.

Application filed March 6, 1897. Serial No. 626,346. (No model.)

To all whom it may concern:

Be it known that we, JOHN WARREN MOORE and JOSEPH ATWOOD WHITE, citizens of the United States, and residents of Philadelphia,

5 Pennsylvania, have invented certain Improvements in Paper-Making Machines, of which the following is a specification.

Our invention relates to certain improvements in paper-making machines known as 10 "Fourdrinier" machines, in which a wire is traversed over an agitated frame, allowing the pulp to form on the wire in such a manner that the fibers will knit together and form a sheet of paper.

15 The object of our invention is to provide for the vertical adjustment of the shake-frame, and particularly the frame described in the Letters Patent of the United States granted to us on February 28, 1899, No. 620,548.

20 In the accompanying drawings, Figure 1 is a side view of sufficient of a paper-making machine to illustrate our invention. Fig. 2 is a sectional view showing the flexible connection between the pedestal and the shake-frame. Fig. 3 is a face view of Fig. 2 on the line 3 3, and Figs. 4 and 5 are views showing 25 other forms of the means of adjustment.

A is the fixed frame of a paper-making machine.

30 B is the shake-frame, in the present instance consisting of upper and lower rails $b b'$, secured to the fixed frame A at one end and coupled to an end frame B' at the opposite or free end. The free end of the shake-frame is suspended from standards D by means of 35 flexible plates d. We also use intermediate suspension-plates d' in many instances, depending from the standards D, especially in 40 long machines; but it will be understood that the shake-frame can be simply suspended at one end and secured to the fixed frame at the opposite end. a is the making-wire, which passes around the breast-roll b^2 and over the rolls b^3 .

45 The details of construction of the machine are similar in many respects to the machine fully described and illustrated in the Patent No. 620,548, mentioned above, and as this in-

vention relates particularly to the means for 50 vertically adjusting the shake-frame we have not described in detail the other parts of the machine.

It has been found by experience that in 55 making certain classes of paper when the machine is run at a certain speed the shake-frame should be in certain positions or angles of inclination to the flow of the pulp to accomplish the best results, and in order to adjust the frame properly we provide the mechanism which we will now proceed to describe.

Adapted to the standard D is a bolt E, having 60 an eccentric section e and a stem e', which passes through the standard and is provided with a nut e^2 . At its opposite end the bolt has 65 a head e^3 , and between this head and the standard is mounted the flexible plate d and a block f. The upper end of the standard is 70 preferably split, as shown in Fig. 2, and extending through the standard is a clamping-bolt f^2 , on turning which the bolt E can be clamped tightly in the standard. The eccentric bolt E can be secured after adjustment 75 to the block f by a set-screw f^3 . We have shown the plate d having a lip d^2 passing over the top of the block; but this is not essential. In some instances the clamping-bolt f^2 or set-screw f^3 , or both, may be dispensed with from the construction shown in Figs. 2 and 3.

80 By loosening the bolt E it can be turned so as to raise or lower the flexible plate d by means of the eccentric portion of the bolt, a suitable wrench being applied to the irregular head of said bolt, and as this plate is secured 85 to the shake-frame that portion of the shake-frame to which the plate is secured will be raised to any extent required. After the eccentric is turned to the proper adjustment the nut e^2 is turned on the bolt, so as to hold the 90 bolt in the set position, and the bolt can be clamped to the standard and to the block f. The said block is engaged by the lips d^2 of the plate d and from them transmits some of the 95 weight upon said plate to the bolt E, the set-screw f^3 when manipulated so as to clamp the block, with its plate, to said bolt serving effectually to prevent rotation of the same

and maintaining it in any position of adjustment.

The flexible plate d is secured to a bracket c on the shake-frame by means of a bolt c' .
 5 In some instances, if desirable, an eccentric bolt, as shown at c^3 , Fig. 2, may be substituted for the bolt c' , so that the adjustment can be made on the shake-frame instead of on the standard, and in some instances, where
 10 an extended adjustment is required, both bolts may be eccentric.

In Fig. 4 we have shown another form of adjusting mechanism, used preferably in the mid-position, in which the standard D' has a
 15 slot d^3 at its upper end, through which passes a bolt E' having a nut on one end and this bolt E' passes through a block F clamped between which and a cap-plate f^4 is the suspension-plate d' . The block F has a lug f^5 , which
 20 extends over the standard, and in this lug is a set-screw g , which rests upon the standard, so that when the bolt E' is loosened the set-screw g can be turned, raising the block F , and with it the flexible plate d' and the shake-
 25 frame B . This device may be used as a substitute for the one shown in Fig. 2 or may be used in connection with it for the intermediate support of the shake-frame, as this intermediate support can be loosened prior to the
 30 adjustment of the end support, so that the end support can be freely raised and lowered and set in the adjusted position, after which the device shown in Fig. 4, when used in the mid-position, can be adjusted to correspond
 35 to the adjustment of the end supports.

It will be understood that while our invention is especially adapted for machines using the flexible suspension-plates other suspension means can be used in connection
 40 with our invention. It will also be understood that there is one of these suspension-plates at each side of the machine at the free end and preferably one at each side of the machine near the middle, and the bolts E of
 45 the opposite suspension device may be connected together by the rod E^2 and operated in unison, if desirable, as shown in Fig. 5, although we have found in practice that in some instances independent adjustment is re-
 50 quired, so as to raise or lower one side of the shake-frame more than another, and we prefer in building the machine to make each adjusting device independent.

In Fig. 5 we have shown an eccentric bushing e^5 , mounted on the eccentric portion e^4 and provided with a clamp f^6 , so that both sides of the shake-frame can be raised or lowered simultaneously or independently or a double adjustment can be secured.

60 We claim as our invention—

1. The combination in a paper-making machine of the Fourdrinier type, of a fixed frame, a shake-frame connected thereto, a standard, means for suspending the shake-frame from
 65 the standard, and means extending at right angles to the suspension means and movable

relatively thereto for raising and lowering the free end of the shake-frame, substantially as described.

2. The combination in a paper-making machine, of a fixed frame, a shake-frame connected thereto, a standard, suspension-plates secured to the standard and to the shake-frame, a movable piece for raising and lowering the shake-frame, the same extending at 75 right angles to the suspension-plates and connecting said plates and the standards, substantially as described.

3. The combination in a paper-making machine, of a fixed frame, a shake-frame connected thereto, a standard, suspension-plates connected to said shake-frame, an eccentric bolt mounted on the standard and adapted to the upper portion of the suspension-plates so that on turning the eccentric bolt the shake-frame can be raised or lowered, substantially as described.

4. The combination in a paper-making machine, of the standard, a shake-frame, a suspension-plate for the shake-frame, a block, a bolt passing through the block and the upper portion of the flexible plate, with means for adjusting the block and plate so as to raise or lower the shake-frame, said bolt securing the suspension-plate and block rigidly to the standard after adjustment, substantially as described.

5. In a paper-making machine the combination of a standard, a shake-frame, a flexible suspension-plate secured to the standard and to the shake-frame, a block, a bolt having an eccentric portion adapted to the block and to an opening in the suspension-plate, a nut on the bolt, and means for preventing the bolt from turning after adjustment, substantially as described.

6. The combination in a paper-making machine, of the fixed frame, a shake-frame secured thereto, standards, flexible plates by which the shake-frame is secured to the standard, one set of standards being at the outer end of the shake-frame and the other intermediate of the length thereof, eccentric bolts adapted to the outer standards whereby the outer end of the shake-frame can be raised or lowered, a block secured to the suspension-plate at the intermediate standard and overhanging said standard, and a set-screw for adjusting said block to correspond to the adjustment of the outer end of the shake-frame, substantially as described.

7. The combination of a standard, a shake-frame, a flexible plate by which the said shake-frame is suspended, an eccentric block non-rotatably held to said plate, and an eccentric bolt passing through the block, substantially as described.

8. The combination in a paper-making machine of the Fourdrinier type, of a fixed frame, a shake-frame connected thereto, a standard, means for suspending the shake-frame from the standard and means movable relatively

to the suspension means for simultaneously raising and lowering both corners of the free end of the shake-frame, substantially as described.

5 9. The combination in a paper-making machine, of a fixed frame, a shake-frame connected thereto at one end, standards, suspension-plates, eccentric bolts mounted on the standards and connected to the suspension-

plates, with means for simultaneously turning said bolts whereby both corners of the free end of the shake-frame may be raised and lowered together, substantially as described. 10
